United States Patent Office

Des. 180,736
Patented Aug. 6, 1957

180,736

JEWELRY STONE FINDING OR SIMILAR ARTICLE

Adolph Katz, Providence, R. I., assignor to Coro, Inc.,
New York, N. Y., a corporation of New York

Application November 23, 1956, Serial No. 43,889

Term of patent 7 years

(Cl. D45—1)

Fig. 1

Fig. 3

Fig. 1 is a plan view of a jewelry stone finding or similar article showing my new design.

Fig. 2 is an edge view from the right of Fig. 1; and
Fig. 3 is an edge view from the left of Fig. 1.

I claim:

The ornamental design for a jewelry stone finding or similar article, substantially as shown.
